UNITED STATES PATENT OFFICE.

JOHN CHARLES REGINALD McCRUDDEN, OF HURSTVILLE, NEAR SYDNEY, NEW SOUTH WALES, AUSTRALIA.

MAGAZINE FOR MACHINE GUNS.

1,425,120.

Specification of Letters Patent. Patented Aug. 8, 1922.

Original application filed June 19, 1920, Serial No. 390,153. Divided and this application filed June 4, 1921. Serial No. 475,070.

To all whom it may concern:

Be it known that I, JOHN CHARLES REGINALD McCRUDDEN, a subject of the King of Great Britain and Ireland, residing at 5 "Fleurbaix," Haig Street, Hurstville, near Sydney, New South Wales, Australia, have invented new and useful Improvements in Magazines for Machine Guns, of which the following is a specification.

10 This invention relates to magazines for machine guns of the automatic recoil type.

The magazine has been devised with a view to augmenting the capacity of the gun for use under exceptional conditions where 15 large magazine capacity and ability for maintaining a sustained fire are called for.

The magazine is shaped as the segment of a circle, and in cross section corresponding with a conventional type of small arm magazine 20 in which the cartridges are contained in laterally staggered order and are retained by a lip at the magazine mouth until withdrawn successively by the bolt action. Its novel and distinguishing features consist in slotting the inner wall of the magazine casting to accommodate an oscillating arm which carries the platform, in applying advance movement to the platform by a spring acting on said oscillating arm, and in sus-

30 pending and latching mechanism by which the magazine and its contents are detachably held on the gun structure in such a manner that their removal and replacement may be effected with great facility and 35 rapidity.

In the accompanying drawings Fig. 1 is a fragmentary side elevational view of a gun with the magazine set in the throat in the breech;

40 Fig. 2 is a longitudinal sectional elevation showing the mounting of the magazine and the cartridge feed mechanism therein and

Fig. 3 is a transverse section on the plane 45 3—3 Fig. 2.

The magazine 1 is a segmental box identical in transverse section with standard service type magazine for shoulder arms and is designed to carry sixty or more small 50 arm service cartridges of .303 or like standard dimensions. It is inserted at its delivery end 2 up into the feed throat 3 in the breech body. Its upper position is determined by its fitting into the pocket in said throat as

in the case of an ordinary service rifle, and 55 it is latched in position by a spring latch 4 which engages a hook staple 5 behind the throat 3. The weight of the magazine 1 and its contents is sustained by carrier arms 6—7 which are supported on a stud hanger 8, said stud hanger being adapted to slide on a fixed carrier pin 9. This pin projects forwardly from a collar 10 which is fixed on the butt collar 11 of the radiator which is a tight fit on the shoulder on the rear end 65 of the barrel 12.

In this magazine, taper-shaped cartridges are packed so that they set in laterally staggered order (the magazine width being greater than the diameter of one cartridge, 70 but less than twice a cartridge diameter), the cartridge at the mouth of the magazine being lightly held by the inturned lips 13 on the cheeks of the magazine 2 but so that when the bolt 14 is moved forwardly, its 75 fore end takes behind the base rim of the cartridge and slides it endwise out of the magazine into the barrel chamber; as each cartridge in turn is thus slid out of the magazine, the next cartridge in order is held 80 in position in the magazine mouth for delivery into the barrel chamber in the next forward movement of the bolt.

The pivot pin 15 supported by the stud hanger 8 carries the feed arm 16 which extends through a slot 17 and acting through the back spring 18 in the magazine supports and moves the platform 19 therein. The arm 16 is swung forwardly by a coiled wire spring 20 and functions through the platform to urge the cartridges in the magazine forward towards its mouth, whence they are taken one by one by the bolt action and delivered into the barrel chamber. This system of construction of the magazine and 95 its mounting offers a positive advantage for re-loading rapidly in action without disturbing the lay of the gun, as the gunner, while still retaining the gun in position,

may in a one-hand movement, release the 100 latch 4 swing the magazine on the pin 15 and slide it forward, thus bringing the hanger 8 off the pin 9. An empty magazine is thus detached by an instant dexterous movement, and by a reverse movement a 105 full magazine inserted. Continuity of firing is therefore interrupted only for a period of a second or two when a magazine

is exhausted; and as each magazine contains a very large number of cartridges, the gun is thus qualified in a special degree for repeated prolonged bursts of firing, which very frequently is a consideration of major importance.

What I claim as my invention and desire to secure by Letters Patent is:—

1. A machine gun magazine comprising a segmental box casing adapted to carry a large number of loose tapered cartridges in staggered order and to reciprocate with the gun barrel, a slot in the inner curved face of said casing, an externally pivoted feed arm extending through said slot, a spring controlling said feed arm, a platform carried by said feed arm, carrier arms adapted to support said casing, and means on said carrier arms for rapidly detaching the magazine from the gun.

2. In a machine gun magazine as set forth in claim 1, a spring latch, a hook staple, a fixed carrier pin, a slot in the gun body and barrel casing, and a stud hanger adapted to be slid forwardly in said slot on said pin when said spring latch is released. 25

3. A machine gun magazine of box case type, but segmental in shape, having its inner rim slotted to accommodate a swing arm, a carrier frame for said magazine including the pivot on which said swing arm is mounted, a carrier lug through which said pivot passes, said lug slidably seated on a bracket fixed on the gun body, a spring adapted to swing said arm towards the magazine mouth, and a fastening latch on the magazine adapted to engage a staple on the breech body. 30 35

In testimony whereof I affix my signature.

JOHN CHARLES REGINALD McCRUDDEN.
